RAIL BOND

Charles H. Mead, Beckley, W. Va.

Application December 1, 1931, Serial No. 578,372

2 Claims. (Cl. 173—278)

This invention relates to an improved electricity conducting connector for railway rails such as is generally referred to in the trade and the art as a bond.

5 It is a matter of common knowledge that the ordinary rail bond is a simple device consisting of a pair of longitudinally spaced terminals individually welded or otherwise fixedly connected with the adjacent ends of companion rails, together with a connecting strap of electricity conducting properties. Manifestly then, when a device of this type is removed for rail repair purposes the terminals are severed from the respective rail-ends and because of the disruptible characteristics of the bond it is generally scrapped and ready for the junkpile. In any event, it is rarely if ever re-used for the reason that it is not regarded as an efficient bond after having once been used.

20 The present inventive conception comprehends a new and novel rail bond characterized by inner and outer sets or pairs of anchoring terminals with conduction connectors therebetween forming a multiple terminal device designed to better fulfill the requirements of an article of this class because of the secondary utility of features embodied therein.

In the drawing:

Figure 1 is a side elevational view of a bond constructed in accordance with the present invention.

Figure 2 is a top plan view of Figure 1.

Figure 3 is a transverse vertical section on the line 3—3 of Figure 1.

35 In the drawing, the rail ends or sections are designated by the numerals 4 and 5 respectively, while the improved device as a whole is distinguished by the numeral 6. This possesses common characteristics of an ordinary rail bond in the sense that it embodies a pair of longitudinally spaced primary terminals 7 and 8 adapted to be welded or otherwise permanently anchored on the rail sections 4 and 5 as indicated in Figure 1.

These terminals 7 and 8 are however joined to an inner pair of longitudinally spaced secondary terminals 9 and 10 through the medium of short connecting webs 11 and 12, the webs 11 and 12 being composed of electricity conducting materials. Then the two terminals 9 and 10 are joined by an intermediate strap-like conductor 13 of appropriate dimensions and length.

The distinguishable sets of terminals may be employed in different ways, but are preferably used in the following manner. The two primary terminals 7 and 8 are initially welded to the rail

heads of the sections 4 and 5 while the terminals 9 and 10 are left free of anchorage or connection, thereby providing a sort of a composite conductor between the terminals 7 and 8. In other words, this conductor is actually made up of the main conductor strap 13, the short webs 11 and 12, and the intermediate terminals 9 and 10.

Assuming now that the rail section 4 is damaged and needs to be replaced, it is obvious that the welded terminal 7 is then severed while the terminal 9 is left temporarily unaltered. Then the substitute rail section is slipped in place and the terminal 7 is discarded by severing the web 11 in order to bring the next adjacent terminal 9 into position for convenient usage.

This terminal 9 is welded to the substitute rail. Assuming then that it becomes necessary to replace the rail 5 at a later date the operatives are instructed to leave the terminal 10 untouched and simply break the terminal 8 loose and to cut the web 12 and throw the terminal 8 away. This then brings the terminal 10 in readiness for use so that now the two inner secondary terminals 9 and 10 are used while the terminals 7 and 8 have been previously discarded in proper order of time. Consequently the single bond has a novel triple period of usage because of the successive steps already pointed out. Of course if both sections 4 and 5 are replaced at the same time both terminals 7 and 8 are cut off and the inner terminals 9 and 10 are then brought into play.

The gist of the invention is in the provision of a multiple terminal equipped rail bond including a pair of simultaneously usable primary terminals, together with a pair of secondary successively or simultaneously usable inner terminals normally free of connection with the rails at the initial installation, plus the short connecting webs 11 and 12, and a normal length connecting strap or web 13 between the terminals 9 and 10.

Admittedly then, this single simple and efficient device affords a novel contribution to the trade and the art calculated to better fulfill the requirements of an article of this class because of the features and advantages previously pointed out and the added convenience of expeditious usage and economy.

It is thought from the foregoing description that the advantages and novel features of the invention will be readily apparent. It is to be understood that changes may be made in the construction and in the combination and arrangement of the several parts provided that such changes fall within the scope of the appended claims.

I claim:

1. In combination, railway rails arranged end to end, and a bond for electrically connecting the rails, comprising conductive terminals fastened to the rails, and an electrical connection between said terminals including intermediate terminals spaced from the first-named terminals and directly disconnected from the rails, conductive webs between the first-named terminals and the intermediate terminals and adapted to be readily severed, and a conductor extending between and connecting the intermediate terminals, said intermediate terminals adapted to be attached to other rails subsequently to the severance of the webs and the detachment of the first-named terminals from the first-named rails and also from said electrical connection.

2. In combination, railway rails arranged end to end, and a bond for electrically connecting the rails, comprising conductive terminals fastened to the rails, and an electrical connection between said terminals including an intermediate terminal electrically connected with one of the first-named terminals and joined by a conductive web with the other of the first-named terminals and directly disconnected from either rail, said intermediate terminal adapted to be attached to another rail subsequently to the severance of said web and the detachment of such other of the first-named terminals from its rail.
